(57) **CLAIM**

The ornamental design for a children's toy, as shown and described.

DESCRIPTION

FIG. 1 is a perspective view of a children's toy;
FIG. 2 is a front view of the children's toy;
FIG. 3 is a back view of the children's toy;
FIG. 4 is a right side view of the children's toy;
FIG. 5 is a left side view of the children's toy;
FIG. 6 is a top view of the children's toy;
FIG. 7 is a bottom view of the children's toy;
FIG. 8 is a rear perspective view of the children's toy with arms extended;
FIG. 9 is a right side view of the children's toy with arms extended; and,
FIG. 10 is a left side view of the children's toy with arms extended.

The level on the rear of the children's toy is shown in broken lines for illustrative purposes only and form no part of the claimed design.
